UNITED STATES PATENT OFFICE

JOSEPH FAUSSE, OF BOSTON, MASSACHUSETTS, ASSIGNOR TO UNITED SHOE MACHINERY CORPORATION, OF PATERSON, NEW JERSEY, A CORPORATION OF NEW JERSEY

MACHINE FOR FORMING AND RE-FORMING TURN SHOES

Application filed September 10, 1928. Serial No. 304,863.

This invention relates to machines for forming and re-forming turn shoes, the illustrated machine having especial utility in operating upon sewed seat turn shoes.

After a turn shoe upper has been assembled wrong side out upon its first last, it is desirable to conform the rear end of the upper and counter intimately to the rear end of the last, for although, when the shoe is turned, the curvatures of the upper and counter are reversed, conformation of these parts to the shape of the second last after turning is facilitated by the fact that they have been conformed to the shape of the first last before turning. Also, in order to facilitate the operation of sewing the upper and counter to the sole about the heel seat of the shoe while on the first last, it is desirable that the upper and counter be forced into the angle between the feather and shoulder of the sole to form a line or groove to guide the turn sewer in the operation of sewing the parts together.

After the shoe is turned and relasted, it is highly important to reshape the upper and counter to the rear end of the second last, to open the crease between the upper and the margin of the sole, and to apply heightwise pressure to the inturned portions of the upper and counter to form a flat and level seat for the reception of the rim of a wood heel.

A method of operating on turn shoes to effect these results is disclosed in the application for Letters Patent of the United States, Serial No. 209,298, filed July 29, 1927, by Herman Newmann.

Objects of this invention are to provide novel and convenient mechanism and apparatus adapted for use in practising the method disclosed in said application.

Accordingly, features of the invention consist in an organization comprising shoe supporting means, a band for conforming the upper and counter to the shape of the rear end of the last, wipers which are organized to advance positively and close yieldingly, and mechanism for operating and controlling the shoe support to render the band and wipers effective for the operations desired.

The wipers may be arranged to be initially

partly closed when in their retracted position so that, as the shoe is moved toward them on the shoe support, the wipers will find and enter the crease between the upper and sole and will open the crease and yield outwardly as the shoe is forced between them. Thus the wipers are caused more easily to enter the crease and assist in properly locating the shoe in the machine. The illustrated machine is organized to draw the shoe support inwardly to force the shoe rearwardly into the band, to hold the shoe from forward movement during the operation of the wipers, and to raise the work support to apply heightwise pressure of the shoe against the wipers to form and compact the inturned portions of the upper and counter. A height gage is provided for engagement with the shoe bottom to assist in locating the shoe for presentation to the wipers and is released from engagement with the shoe during the upward pressure of the shoe support to permit the pressure of the shoe to be taken by the wipers.

For some purposes it is desirable that the opening between the wipers be controlled by the position of the heel band, the wipers being held open when the band is open to receive the shoe and being allowed to close as the band is closed on the shoe. Accordingly, provision is made for causing the closing movement of the wipers, through the yielding mechanism which operates them, to be limited by engagement with the band and for causing the wipers to apply additional pressure to the band to cause its end portions to close more tightly upon the shoe.

These and other novel combinations and arrangements of parts will appear more fully from the following detailed description when read in connection with the accompanying drawings and will be pointed out in the appended claims.

In the drawings,

Fig. 1 is a perspective view of a machine embodying the present invention;

Fig. 2 is a side elevation, mostly in section, of the machine shown in Fig. 1;

Fig. 3 is a plan view, partly in section, of the heel band and its operating mechanism;

Fig. 3^a is a detail view, in elevation, of parts shown in Fig. 3;

Fig. 4 is a plan view, partly in section, of the novel wiper-operating mechanism of the machine;

Fig. 5 is a section detail view taken on the line 5—5 of Fig. 4;

Fig. 6 is a perspective view, partly broken away and in section, of the head of the machine and showing its left-hand side; and

Fig. 7 is a diagrammatic view of the cams for actuating various operating instrumentalities of the machine.

The illustrated machine for forming or re-forming the heel portions of sewed seat turn shoes comprises a shoe support or jack which is similar in many respects to that disclosed in United States Letters Patent No. 1,558,737, granted October 27 1925, on application of Ronald F. McFeely, and operating instrumentalities which are in their general organization similar in many respects to those disclosed in United States Letters Patent No. 1,583,044, granted May 4, 1926, on application of Charles H. Hoyt. The machine illustrated as embodying the present invention is particularly adapted for operation on sewed seat turn shoes and its organization for that work will be herein particularly described and explained, it being understood that such portions of the machine as are not fully described herein will be found disclosed in the above-mentioned patents. The operating instrumentalities for conforming the rear end of an upper to a last and for treating the turned in portion of the upper to be hereinafter more fully described are carried by a head 10 which is mounted on a column 12. In the head 10 extending fore and aft thereof is a cam shaft 14 carrying a cam block 16 on which are formed various cams by which the operating instrumentalities of the machine are actuated. The shaft 14 carries a worm wheel 18 which is driven by a worm shaft 20 at right angles to the shaft 14 and arranged to be driven at times through a cone friction clutch comprising members 22, 24 (Fig. 4). The clutch member 24 is formed on a pulley 26 loose on the shaft 20 and driven from a suitable source of power, for example an electric motor mounted on the shelf 28 at the base of the column 12 (Fig. 1). Suitable clutch operating and stopping mechanism similar in general to that disclosed in Letters Patent No. 1,583,044 above mentioned is provided for causing a single revolution to be imparted to the cam shaft 14 in each cycle of the machine. The clutch mechanism is arranged to be operated to start the machine by a rearward thrust on a knob 30 on a sliding rod 32 connected at its rear end to the clutch tripping mechanism. The illustrated machine is provided with an external band brake 33 having one end fixed to a pin 35 and

the other end connected to an arm 37 on a rock shaft 39, which is operated to apply the brake by the same means disclosed for applying the brake in Letters Patent No. 1,583,044.

The shoe support or jack comprises a frame 40 (Fig. 2) pivoted on a shaft 42 for swinging movement toward and from the machine. Mounted for endwise movement in the frame 40 is a post 44 having at its upper end a heel pin 46 (Fig. 1). Extending forwardly from the post 44 is a rigid bar 48 on which is a slide 50 carrying a pawl 52 adapted to engage teeth 53 in the lower edge of the bar 48, to hold the slide 50 in adjusted position. On the slide 50 is a toe rest 54 which can be adjusted vertically by turning a thumb head 56, the adjustment being held by a pawl 58 arranged to be lifted by the operator. Adjustably connected to the post 44 by mechanism to be described is a rod 60 (Fig. 2) to the lower end of which is connected a rack bar 62 meshing with a pinion 64 loose on the shaft 42 and having a ratchet wheel 66 integral therewith or fixed thereto. A member 68 mounted to rock freely on the shaft 42 carries two pawls 70, 72 operated by springs 74 to engage the ratchet wheel 66 when permitted to do so by pawl lifters or shields 76 which are arranged for adjustment circumferentially of the shaft 42 by any suitable means. The position of the shields 76 determines, of course, the time in the movement of the pawl carrying member 68 when one of the pawls 70, 72 will engage the teeth of the ratchet wheel 66. It will be understood that the pawls 70, 72 are one-half a tooth more or less than 180° from each other so that, after the pawls leave the lifters, movement of the member 68 through the space of half a tooth only is necessary to cause engagement of one or the other of the pawls 70, 72 with the ratchet wheel 66.

The rock member 68 is connected at 78 to a rod 80 fixed to the lower end of a cylinder 82 in which is a head 84 connected to the lower end of a rod 86. Between the head 84 and a plug 88 fixed in the upper end of the cylinder 82, and through which the rod 86 freely passes, is a strong compression spring 90. The upper end of the rod 86 is connected to a lever 92 operated by power of the machine in a manner to be explained. Considering the rods 80 and 86 as one, the spring 90 and cylinder 82 provide a yielding connection in the rod, opposing extension thereof by the pull of the lever 92 which actuates the member 86 and causing the pawls 70, 72, to engage the ratchet wheel 66 and hence to lift the shoe support.

The lower end of the rack bar 62 is engaged by a lever 94 fulcrumed at 96 to the frame 40 and having its rearward arm connected by a link 98 to a treadle 100 pivoted at 102 and normally raised by a tension spring 104.

It will be seen that since the pivot 96 of the

lever 94 is disposed rearwardly of the pivot 42 of the frame 40 depression of the treadle will swing the frame 40 rearwardly. If such swinging movement of the frame rearwardly is opposed, however, the lever 94 will turn on its pivot 96 and push upwardly on the rack bar 62 thus lifting the post 44. The operator, therefore, can, by opposing inward movement of the shoe, cause the shoe to be raised by depression of the treadle. Preferably, however, the adjustment between the rods 44 and 60 will be so set that the shoe will be presented at the proper height merely by its rearward movement.

Connected at 106 to the frame 40 is a rack bar 108 the inner end of which is guided in meshing relation to a pinion 110 keyed to a shaft 112. The rack bar 108 is guided by a member 114 (Fig. 6) mounted to swing freely on the shaft 112. The member 114 (Fig. 2) is bored to receive a plunger 116 which has a reduced portion extending through the member 114 and provided with a stop nut 118. On the reduced portion of the plunger 116 is a spring 120 which yieldingly maintains the plunger in forward position. When the frame 40 is swung inwardly of the machine a pin 122 on the rack bar 108 engages the plunger which affords the resistance necessary to cause depression of the treadle to raise the post 44 and the shoe causing the shoe sole to engage a bottom rest or height gage 124, if the shoe is not already in contact with it. The gage limits or prevents upward movement of the shoe and insures that the shoe will be located in proper relation to the wipers and heel band to be described.

The heel end clamping means herein shown is substantially like that disclosed in the Letters Patent No. 1,583,044 above referred to. To receive and embrace the rear end of the shoe a flexible heel band 130 is supported at its rear end by a clip 132 secured to a stud 134 which is arranged for a slight vertical movement in a carrier slide 136. The opposite side portions of the band are slidably supported by clips 138 which are fast on studs 140 (Fig. 3a) vertically and rotatably movable in supporting slides 142 which are adjustably held by bolts 143 on horizontally swinging arms 144. To assist in pressing the band against the sides of the shoe to force the upper and counter into conformity with the contour of the sides of the last the studs 140 carry blocks 146 which have curved contact faces for engaging the band 130. A similar support for the rear end of the band is afforded by a backing member 148 (Fig. 2) shown as integral with the stud 134. To assist in pressing the band inwardly against the corners of the rear end of the shoe arms 150 are pivotally mounted at 152 on the upper enlarged end of the stud 134 and have pivoted on their outer ends contact members 154 for engaging the band 130. Integral also, in the construc-

tion shown, with the stud 134 are arms 156 in the ends of which are mounted spring plungers 158 which engage the arms 150 and, through the contact members 154, maintain a constant pressure on the curved rear "corners" of the band sufficient to contract the band slightly in such manner that when the shoe is forced rearwardly into it an effective wiping and conforming pressure is applied around the corners of the rear end of the shoe. In order to limit adjustably the contraction of the band by the pressure of the contact members 154, the arms 150 carry stop screws 160 which engage the member 148.

For closing the band and forcing it inwardly against the sides of the heel end portion of the shoe the machine has lever arms 162 connected to the arms 144 to swing them inwardly. The connections between the arms 162 and the arms 144 comprise adjustable links 164 consisting of socket members 164 which are pivoted on the arms 162 and rods 166 pivoted on the arms 144 and extending within sleeve portions 168 which are threaded in the socket members 164, the members 168 being confined on the rods 166 by means of nuts 170 keyed to the members 164. As thus constructed the connections provide for adjustment of the pressure applied by the band and adjustment for different sizes of shoes through turning movement of the sleeve members 168 to lengthen or shorten the distance between the arms 162 and 144.

Operative movement of the arms 162 to close the band about a shoe (Fig. 3) is effected by means of a slide 172 which carries a T-shaped member having a head 174 in engagement with sliding rack bars 176 operatively connected to gear segments 178 on the arms 162. The shank 180 of the T-shaped member 174 extends within the slide 172 and carries a spring 182 through which movement is imparted yieldingly to the band closing connections when the slide 172 is moved rearwardly. For imparting such movement to the slide the machine has a shaft 184 on which is formed a pinion 186 in engagement with rack teeth 187 on the upper side of the slide 172, the shaft having also a pinion 188 which is engaged and operated by a gear segment 189 on a bell crank lever 190 (Fig. 6) provided with a roll 192 in engagement with a cam face 194 on the rear end of the cam block 16. Return springs 196 acting on the slide 172 serve to hold the roll 192 in engagement with its cam and when permitted by the cam to swing the arms 162 and their connected mechanism outwardly to release the shoe.

The slide 136, which as above explained serves to support the rear end of the heel band, is an adjustable slide whereby the band may be moved bodily lengthwise of the shoe to determine the relation of the wipers to the heel end face of the shoe, as may be nec-

essary or desirable in changing from one size or style of shoe to another in order to vary the extent of overwiping movement of the wipers at the end of the shoe. It will be understood that in such adjusting movement of the band its opposite side portions slide freely along the guideways provided by the clips 138. For effecting the adjusting movement of the slide 136 the machine has a pinion 200 which engages rack teeth on the slide 136 and is integral with or fast on a shaft 202 provided on its outer end (Fig. 1) with an adjusting handle 204 having a pawl for engagement with fixed ratchet teeth 206 which hold the band against rearward movement. The pawl is lifted by a knob 207 to permit backward adjustment of the band.

A further adjustment for different sizes of shoes, having in view the application of the forming pressure at substantially the same location on different shoes, is afforded by the slides 142 which carry the devices for closing the band, the slides being adjustable lengthwise on the arms 144 which are provided with clamping bolts 143 to hold the slides in position.

As above stated, the supporting stud 134 of the heel band and the studs 140 on which are mounted the supporting clamps for the side portions of the band have a slight vertical movement on their supporting members. The purpose of this arrangement is to permit the band to be moved vertically with the shoe, as will be hereinafter more particularly explained.

Rearward movement of the band operating slide 172, Fig. 2, operates the lever 92 to lift the shoe and for this purpose the under side of the slide 172 is provided with rack teeth which engage a toothed segment 210 formed as part of the lever 92 so that rearward movement of the slide 172 swings the lever 92 upwardly about its supporting shaft 212 causing it to act through the rod 86, 80 to actuate the pawls 70, 72 and lift the shoe support in conjunction with the closing of the band.

It is desirable that the shoe be forced yieldingly rearwardly into the band prior to the closing of the band. This is effected by mechanism acting through the pinion 110 upon the rack bar 108. Referring to Fig. 1, the outer end of the shaft 112 has fixed to it a ratchet wheel 220 which is operated by a pair of pawls 222, 224 arranged similarly to the pawls 70, 72 and carried by a rocking member 226. Pawl shields or lifters similar to those for the pawls 70, 72 are provided which are carried by a sleeve 228 adjustably held by a screw 230. The pawl-carrying member 226 is connected by a link 232 to an arm 234 pivoted on a fixed stud 236 at its upper end. A cam arm 238 has its lower end mounted on the same pivot 236 and carries a roll 240 which engages a cam 242 on the

cam block 16. The arms 234 and 238 have rearward offsets 244, 246, respectively, which are connected together by a yielding mechanism including a spring 248 and a lighter spring not shown. This yielding mechanism may be similar to that disclosed for a similar purpose in the Letters Patent No. 1,583,044 above referred to. By operation of a handle 250 the action of the springs may be controlled to vary the yielding action of the mechanism.

When the shoe support is swung toward the machine the rack bar 108 causes the ratchet wheel 220 to rotate and since the pawls 222, 224 are then held away from their ratchet by their shields or lifters the support may be moved freely in or out. When the machine starts the cam 242 swings the arm forwardly, the arm 238 acting through the yielding connection to swing the arm 234 rearwardly, thus turning the pawl carrier 226 causing the pawls 242, 244 to move off the shields or lifters, engage the ratchet and turn the pinion 110, Fig. 2, clockwise to draw a shoe on the shoe support yieldingly into the band 130.

For forcing the upper and counter into the angle between the feather and shoulder of a sole of a turn shoe before it is turned and for opening the crease between the margin of the sole and the upper and pressing the inturned portion of the upper after the shoe is turned, wipers similar to lasting machine wipers are provided. These wipers, however, instead of being positively advanced and closed, as is usual in lasting machines, are positively advanced and yieldingly closed. Moreover, they may be partially closed by yielding means before they are advanced, that is, while in retracted position in order that they may be made more readily to enter the crease between the sole and upper of a shoe presented to them on the shoe support.

A pair of wipers 260, Fig. 4, is carried by a slide 262 which is mounted for movement lengthwise of a shoe in the guideway in the frame. To support the wiper plates the slide 262 has secured thereto a plate 264, Fig. 2, which has an upstanding rib 266 extending into a groove in the wiper plates to guide them in their swinging movements, the plates being pivoted together by means of a pin 268, Fig. 4, located at the axis of curvature of the guiding rib 266. Overlying the wiper plates and secured to the slide 262 by screws 270, which also hold the plate 264 in place, is a thrust plate 272 which, as shown in Fig. 4, is curved similar to the wipers and is extended forwardly for a considerable distance on each side to sustain the upward thrust of the wipers when the shoe is lifted by the jack lifting mechanism. At the rear end the wiper slide 262 is recessed to receive the forward portion of a rear slide 276, the two slides being held in fixed relation by a trans-

verse shaft 278. The rear slide 276 carries a roll 280 which projects into a cam groove 282 in the cam block 16, Fig. 2, and is operated by the cam to impart bodily advancing movement to the wipers, the wipers being advanced and held in advanced position during the major portion of the cycle as will be seen from the cam chart shown in Fig. 7.

Yielding closing movement is imparted to the wiping plates 260 simultaneously with their positive advancing movement by the following mechanism: Wiper-carrying slides 284 have secured to their inner ends (Fig. 5) underlying wiper-supporting plates 286 and overlying thrust plates 288, the plates 286 having slots 290 to receive pins or rolls 292 on the wiper plates 260, the wipers being thus guided in their movement lengthwise of the shoe. The closing slides 284 are made hollow to receive operating slides 294 threaded into which are screw plugs 296 having stems 298 with squared outer ends extending through holes in the slides 284 and accessible at the outside of the machine frame so that they may be turned with a wrench. Between the plugs 296 on the operating slides 294 and the wiper-carrying slides 284 springs 300 are introduced so that as the slides 294 are operated inwardly they act through the springs 300 yieldingly to move the wipers toward each other in their closing movement. The pressure of the springs 300 may be varied by turning the plugs 296 and any desired amount of initial tension may be given the springs 300 by turning the plugs 296 since inward movement of the slides 284 relatively to the operating slides 294 is limited by projections 301 on the wiper-carrying slides 284 which engage the operating slides 294. To operate the slides 294 they have rack teeth on their rear faces meshing with pinions 302 mounted on fixed axes in the frame. Angle levers 304 fulcrumed at 306 on the frame have toothed segments 308 meshing with the pinions 302 and also have toothed segments 310 meshing with a slide 312. The slide 312 has a bridge piece 313 extending across the slides 262, 276 at their juncture, has side portions located in recesses on opposite sides of the slide 262, and is held for movement with the slide 262 by the shaft 278.

In order to vary the closing movement of the wipers as may be required by different sizes or styles of shoes the machine is provided with means for adjusting the rack slide 312 relatively to the slide 262 thus moving the wiper-operating slides 294 inwardly or outwardly without affecting the position of the slide 262. For this purpose the transverse shaft 278 has on its opposite ends eccentric portions fitted in blocks 314 which are movable vertically in recesses formed in the opposite side portions of the slide 312. For turning the shaft 278 to adjust the slide 312, a shaft 316 is rotatably mounted in the stud

236 hereinbefore mentioned, the shaft 316 having on its inner end a head 318 provided with a transverse slot to receive a projection 320 on the end of the shaft 278. The shaft 316 has fixed thereto a hand wheel 322 which is held in outward position by a spring 324. By pushing in on the hand wheel 322 and turning it, the slot in the head 318 is made to engage the projection 320 on the end of the shaft 278 whereupon the shaft 278 may be turned to adjust the slide 312 as desired. A suitable detent is provided to prevent accidental turning of the shaft 278. Upon release of the hand wheel, the spring 324 acts to move the shaft 316 outwardly so that it does not interfere with the operative movement of the slide 312.

Under some conditions it is desirable to have the normal or initial position of the wipers 260 determined in accordance with the position of the heel band which, of course, is initially open. For this purpose the construction shown in Figs. 4 and 5 is provided. The wiper carriers 284 are slotted at 330 to receive screws 332 which are threaded into blocks 334. To the blocks 334 are fastened, by means of screws 338, L-shaped stop members 336 which engage surfaces on the blocks 146 which engage the band 130. In this construction, when the band is opened to receive the shoe the wipers are also held open by the stops 336 and as the band closes the wipers are also closed by the springs 300. As the springs 300 are tensioned by operation of the wiper-closing slide 312 the wipers are yieldingly forced toward each other and toward the band until the stops 336 engage the band. The inward closing movement of the wipers is then arrested and the tension of their operating spring 300 is applied to the band to force the ends of the band more tightly against the sides of the shoe. The amount of closing movement which the wipers are permitted to have relatively to the band may be varied by loosening the screws 332 and adjusting the stops 336 toward or from the shoe. The outer portions of the slots 330 are enlarged to permit access to the screws 338 so that the stops 336 may be removed if desired. When the stops are removed the wipers are held initially in partly closed position by their springs 300 against which they can yield outwardly to permit a shoe to pass between them into the band.

When a shoe on the support has been presented against the height gage 124 and drawn yieldingly backwardly into the band by mechanism described as acting upon the rack bar 108 through the spring 248 and the band has been closed, it is desirable to force the rear end of the shoe more firmly against the band and to hold it positively against forward movement during the forward movement of the wipers over the shoe bottom. For this purpose mechanism shown in Figs.

2 and 6 is provided. Fixed on the shaft 112 which carries the pinion 110 for operating the rack bar 108 is a second ratchet wheel 340, Fig. 6, with which a pawl 342 co-operates. This pawl is on a pawl carrier 344 which is connected by a link 346 to the lever 92. A pawl shield 347 is provided for the pawl 342 which shield is carried by a sleeve 348 on the shaft 112. The sleeve 348 has a slotted flange 350 held by a screw 352 and by loosening the screw the pawl shield may be adjusted to vary the time when the pawl will be permitted to engage the ratchet wheel 340. When the lever 92 is actuated by the cam 194 through the mechanism described to raise the work support, the pawl 342 will be operated and will, when permitted by the shield 347, engage the ratchet wheel 340 causing the work support not only to be held positively from forward movement in response to the forward movement of the wipers but also to move rearwardly to seat the rear end of the shoe more firmly into the band.

It will be seen from the cam chart, Fig. 7, that the cam 194 has a first rise between 90° and 180° and a further and lesser rise just beyond 180°. The first rise operates through the heavy spring 90 to lift the work support and at the time the second rise acts the pawl 342 operates to lock the shoe support from outward movement, and force the shoe backward into the band. The operation of the lever 92 by the second rise further tensions the spring 90. At this time the wipers are closed and it is desirable that the upward pressure of the shoe support be effective against the wipers to shape the upper. Accordingly, mechanism is provided to lift the height gage 124 at this time to permit the upward pressure augmented by the second rise of the cam 194 to be effective against the wipers. For this purpose the height gage has rack teeth 354 formed thereon, Fig. 2, which are engaged by a pinion 356. On the same shaft as the pinion 356 is a pinion 358 engaged by a rack 360 on a horizontal rod 362, the rack being urged rearwardly by a spring 364. The rod 362, Fig. 6, is connected at 366 to an arm 368 pivoted at 370 and carrying a roll 372 which engages a cam 374, Fig. 2, on the outer margin of the front face of the cam block 16. The arm 368 has a rearward projection 376 through which a screw 378 is threaded. The screw 378 engages the frame adjustably to limit rearward movement of the arm in response to the spring 364 or upward pressure of the shoe. At a point on the cam 374, corresponding to the position of the second rise of the cam 194, is a drop which permits the roll 372 to move rearwardly and hence permits the height gage 124 to rise. Thus the upward thrust of the shoe is taken by the wipers with the result that the upper is compacted thereby. The amount of upward movement which the gage 124 is per-

mitted to have may be varied by adjusting the screw 378.

Heightwise adjustment of the height gage 124 is effected by lifting a knob 380 and turning a thumb head 382 through mechanism disclosed in the Hoyt patent hereinbefore mentioned.

During the described upward movement of the shoe against the wipers the band, which at this time is tightly closed upon the shoe, may move upwardly with the shoe the distance necessary and hence does not interfere with the pressure of the shoe against the wipers.

For effecting heightwise adjustment of the post 44 relatively to the rod 60 improved mechanism is provided as shown in Fig. 2. On the upper end of the rod 60 is loosely fitted a sleeve 390 in the upper end of which is threaded a headless screw 392 which engages the upper end of the rod 60. The lower end of the post 44 is bored at 394 to receive the sleeve 390, the bore being deep enough to avoid contact with the screw 392 in different adjustments of the screw. The outer shell of the bored portion of the post 44 is formed with oppositely disposed tongues 396. The upper portion of the sleeve 390 is reduced in diameter to pass between the tongues 396 and the full sized portion of the sleeve 390 is formed with two series of three recesses 398, the recesses of each series being located at different distances vertically from the lower end of the sleeve and each recess of one series being opposite the corresponding recess of the same height in the other series. The tongues 396 are adapted to engage any pair of recesses on the sleeve 390 and adjustment is made by lifting the post 44 and turning the sleeve by its milled lower portion which is accessible for hand manipulation. The three height adjustments thus obtainable correspond in general to the heights of the post 44 required for children's, women's, and men's lasts. Since lasts of these three general classes vary somewhat in height the screw 392 is provided for making fine adjustments. By removing the post 44 the slotted upper end of the screw 392 is made accessible with a long screw driver and may be thus turned to effect fine adjustment of the height of the sleeve 390 with respect to the rod 60. When this adjustment has been properly effected for say children's lasts of one make, adjustment of the post 44 by means of the other recesses 398 will take care of women's and men's lasts of the same make. A set screw 400 is provided in the sleeve 390 to engage the screw 392 to maintain it in adjusted position, the set screw being accessible through a suitable opening in the jack frame 40.

It is to be understood that either of two operations may be performed by the machine on a sewed seat turn shoe, that is, one operation on the shoe after it is lasted and before

it is turned and the other operation on the shoe after it is turned and relasted.

In operating on a shoe in the first instance the object is to conform the upper and counter to the first last and to force their overlasted margins into the angle between the feather and shoulder of the sole to form a line or crease to guide the turn sewing machine operator in placing the seam which connects the upper and counter to the sole about the periphery of the heel seat portion of the sole. For this purpose, the operator takes a turn shoe the upper of which has been lasted wrong side out upon its last, the lining about the heel end being turned down out of the way and exposing the counter. He places the last upon the heel pin 46 and adjusts the toe rest 54 lengthwise and heightwise so that the heel seat portion of the sole will be substantially horizontal when the shoe is presented in the machine. He will then depress the treadle 100, causing the post 44 to swing toward the machine. The shoe is pushed rearwardly between the wipers which may at that time be held in initially partly closed position by their springs 300. If the stops 336 are in use, the wipers will be held open by engagement of the stop with the band 130. The starting knob 30 is now pushed rearwardly to start the power cycle of the machine whereupon the cam 242 will act through the mechanism described yieldingly to draw the shoe support rearwardly and force the rear end of the shoe tightly into the closed end of the band 130. The first rise of the cam 194 will then act as described to lift the shoe support through the spring 90 and the band will be closed by action of the same cam. The wipers will now have been advanced and closed by their operating cam 282 but before they have been advanced far enough so that their forward pressure is liable to displace the shoe the second rise of the cam 194 will be effective to cause the pawl 342 to engage the ratchet wheel 340 and lock the shoe support against outward movement and move it positively rearwardly to cause the shoe to be forced more tightly into the band which at the same time is more tightly closed. As the wipers are positively advanced by their cam 282 the wiper-closing mechanism acts through the springs 300 to close yieldingly the forward ends of the wipers against the sides of the shoe. During the action of the second rise of the cam 194 the height gage 124 is lifted and the final lifting of the work support by the cam 194 through the pawl 342 presses the shoe hard against the wipers. Thus, the upper and counter by the pressure of the wipers are forced into the groove or angle between the feather and shoulder of the sole and a groove or line formed on the counter which indicates to the sewing machine operator where the seam should be located with respect to the counter. When at

the end of the cycle the machine stops with the wipers and band released, the plunger 116 forces the shoe support forwardly out of the machine.

In the second instance of the use of the machine, that is, upon a sewed seat turn shoe after it has been turned, the object is to conform the upper and counter intimately to the shape of the second last, open up the crease between the feather of the sole and the upper and by application of pressure heightwise of the shoe to the inturned portion of the upper and counter to form a level and even seat for the rim of a wood heel which will be applied after the peripheral portion of the sole has been trimmed away by the heel seat fitting operation, the opening of the crease being preparatory to that operation. The presentation of the shoe and the operation of the machine will in this case be substantially as described. It is advantageous, however, for this operation to have the wipers held yieldingly in partly closed position as will be the case if the stops 336 are removed or rendered inoperative to hold the wipers open. As the shoe positioned by the height gage 124 is moved rearwardly the wipers in their partly closed position readily find the crease between the sole and upper at the rear of the shoe and as the shoe is moved rearwardly, they are forced open and follow the crease along the sides of the heel seat portion of the sole. When the machine operates the wipers are advanced positively to enter the crease at the rear end of the shoe, the extent of their effective advancing movement being controlled by forward or rearward adjustment of the band by means of the handle 204. The springs 300 through which the wipers are closed are stiff enough to cause the wipers to be forced against the seam which holds the upper and sole together and can then yield to prevent injury to the seam while the wiper-operating slides 294 complete their movement. The upward pressure given to the shoe support after the wipers have closed and the height gage 124 has been lifted results in pressing the inturned portion of the upper against the flat lower faces of the wipers to form an even seat for the rim of the wood heel. The conforming pressure of the band ensures that the counter portion of the shoe is reshaped to correspond intimately to the shape of the last, the result being a shapely shoe prepared for the next operation without the necessity of hand operation thereon.

Having thus described my invention, what I claim as new and desire to secure by Letters Patent of the United States is:

1. In a machine for operating on turn shoes, the combination of a shoe support movable toward and from the machine, wipers constructed and arranged to engage the bottom of a lasted shoe and initially yieldingly closed to permit the shoe to enter between

- them and force them apart, means arranged to engage the sides of the shoe below the wipers, and operating means for causing movement of the side engaging means and the wipers to conform the upper to the shape of the last and yieldingly to close the wipers to shape the inturned portion of the shoe upper. 5
2. In a machine for operating on turn shoes, a combination of a shoe support, wipers arranged to engage over the shoe bottom and initially partly closed to permit the wipers to enter the crease between the upper and the sole of the shoe, means arranged to engage the sides of the shoe below the wipers, and operating means for first causing relative movement of the side engaging means and the wipers to cause the upper to conform to the shape of the last and then yieldingly to close the wipers to shape the inturned portion of the shoe upper about the heel seat. 10
3. In a machine for operating on turn shoes, the combination of a shoe support, wipers initially yieldingly closed to permit the shoe to enter between them and force them apart, a heel band, means for closing the band to cause the upper and counter to conform to the shape of the last, and means for yieldingly closing the wipers to shape the inturned portion of the shoe upper and counter. 15
4. In a machine for operating on turn shoes, the combination of a shoe support, wipers initially yieldingly closed to permit the shoe to enter between them and force them apart, a heel band, means for closing the band to cause the upper and counter to conform to the shape of the last, and means for positively advancing and applying inward, yielding, closing pressure to the wipers to shape the inturned portion of the shoe upper and counter. 20
5. In a machine for operating on turn shoes, the combination of a shoe support, wipers arranged to engage the inturned portion of the upper and counter, means beneath the wipers constructed and arranged to conform the upper to the shape of the last, and means for yieldingly closing the wipers to shape the inturned portion of the upper and counter. 25
6. In a machine for operating on turn shoes, the combination of a shoe support movable toward and from the machine, wipers yieldingly closed to permit the shoe to enter between them and force them apart, a heel band, means for causing the upper and counter to conform to the shape of the last, means for causing the wipers to shape the inturned portion of the upper, and means for effecting relative vertical movement between the shoe support and wipers to cause them to apply pressure to the upper and the counter heightwise of the shoe. 30
7. In a machine for operating on turn shoes, a combination of a shoe support, a height gage to engage the shoe bottom, wipers initially closed and arranged to enter the crease between the sole and upper of the shoe when the shoe is pressed against the height gage, a heel band, means for closing the band to cause the upper to conform to the last, means for causing the wiper to shape the upper, means for effecting relative heightwise movement between the shoe support and wipers to apply pressure to the inturned upper and counter, and means for retracting the height gage during the heightwise pressure. 35
8. In a machine for re-forming the rear portions of sewed seat turn shoes, the combination of means to present a shoe and last in predetermined vertical position, wipers positioned to enter the crease between the sole and upper of a shoe so presented, a band arranged to close on a shoe upper and to force the upper and counter into conformity to the rear end portion of the last, means for closing the wipers yieldingly to force them into the crease against the stitches, and means for effecting heightwise pressure between the wipers and the last to compact the inturned portion of the upper and form a level seat for the rim of a wood heel. 40
9. In a machine for re-forming the rear portions of sewed seat turn shoes, the combination of a support to hold the last and present a shoe thereon, a height gage for determining a vertical position in the shoe, wipers positioned to enter the crease between the sole and upper of the shoe so presented, a band arranged to close upon the rear portion of the upper and force the upper into conformity with the rear portion of the last, means for closing the wipers yieldingly to force them into the crease against the stitches about the heel seat and for advancing them positively, means for raising the shoe support toward the wipers to compact the inturned portion of the upper, and means for retracting the height gage to permit the shoe to be effectively pressed against the wipers to form an even seat for the rim of a wood heel. 45
10. In a machine of the class described, the combination of a pair of wipers, a slide on which the rear ends of the wipers are pivoted, means for advancing the slide positively, and mechanism between said slide and the forward ends of the wipers including springs for yieldingly forcing the forward ends of the wipers inwardly in conjunction with their positive forward movement. 50
11. In a machine of the class described, the combination of a wiper carrier, a pair of wipers pivoted thereto at their rear ends, power operated means for moving the carrier, slides extending transversely of the direction of movement of the carrier to which the forward ends of the wipers are pivoted, means for operating said slides from movement of the carrier, and springs between said slides and their operating means, the construction being such 55

that the wipers are positively advanced and yieldingly closed.

12. In a machine of the class described, a combination of a pair of pivoted wipers, a power operated carrier for positively advancing the wipers over the shoe bottom, and mechanism between said carrier and the forward ends of the wipers including springs for yieldingly forcing the forward ends of the wipers toward each other when the carrier is advanced.

13. In a machine for operating on a relasted sewed seat turn shoe, the combination of a shoe support, means for subjecting all parts of the counter portion of the shoe simultaneously to pressure against the last, means for separating the feather of the sole from the upper, and means for effecting heightwise pressure between the separating means and said last to flatten the inwardly disposed portion of the upper.

14. In a machine for reshaping the rear portions of a relasted sewed seat turn shoe, the combination of a last support movable toward and from the machine, means arranged to enter the crease between the upper and sole at the sides of the heel seat as the shoe is presented on said support, means for pressing all parts of the counter portion of the shoe into conformity with the last, means for advancing the crease engaging means lengthwise of the shoe to enter the crease at its rear end, means acting simultaneously to apply yieldingly pressure to the crease engaging means at the side of the heel seat to set the crease engaging means up against the heel seat seam, and means for lifting the support to cause the crease engaging means to flatten the inturned portion of the upper with which it is in engagement.

15. In a machine of the class described, the combination of a pair of wipers, an actuating slide on which the rear ends of the wipers are pivoted, power-operated means for advancing the actuating slide positively, transverse operating slides connected to said actuating slide, transverse wiper carrying slides to which the forward ends of the wipers are connected, means for limiting movement of the wiper carrying slides relatively to their operating slides, and springs between the operating slides and wiper carrying slides.

16. In a machine of the class described, the combination of a wiper carrier, a pair of wipers pivoted thereto at their rear ends, power-operated means for moving the carrier, slides to which the forward ends of the wipers are pivoted, operating means for said slides, springs under initial tension between the slides and their operating means, and means for varying the initial tension of the springs.

17. In a machine for operating on turn shoes, the combination of a shoe support, a pair of wipers, a heel band, means for closing

the band to cause the upper and counter to conform to the shape of the last, means for yieldingly closing the wipers to shape the inturned portion of the shoe upper and counter, and stops carried by the wipers and engaging the heel band to limit closing movement of the wipers.

18. In a machine for operating on turn shoes, the combination of a shoe support, a pair of wipers, yielding means tending to close the wipers, a heel band, means for limiting closing movement of the wipers in accordance with the position of the heel band, means for closing the band to cause the upper and counter to conform to the shape of the last, thereby permitting the wipers to close, and means for applying inward pressure to the wipers to shape the inturned portion of the shoe upper and counter, said pressure being applied to the heel band through said limiting means after the wipers have closed.

19. In a machine for operating on turn shoes, the combination of a shoe support, wipers arranged to engage the inturned portion of an upper and counter, a band beneath the wipers constructed and arranged to conform the upper and counter to the shape of the last, means for yieldingly closing the wipers to shape the inturned portion of the upper and counter, and means to cause the closing pressure of the wipers to be taken by the band after the wipers have closed.

20. In a machine for operating on relasted sewed seat turn shoes, the combination of a shoe support, an end embracing band for subjecting all parts of the counter portion of the shoe simultaneously to pressure against a last, means for separating the feather of the sole from the upper, and means for effecting heightwise pressure of the shoe against said separating means to shape the inturned portion of the upper.

21. In a machine of the class described, the combination of a wiper carrier, a pair of wipers pivoted thereto at their rear ends, carrier slides to which the forward ends of the wipers are pivoted, operating means for said slides, springs under initial tension between the slides and their operating means, and means readily accessible at the outside of the machine for varying the initial tension of the springs.

22. In a machine of the class described, the combination of a heel band for conforming an upper to the rear end of a shoe, wipers for treating the overlasted portion of the upper and counter, a shoe support movable toward and from the machine to present a shoe to the band and wipers, means for adjusting the shoe support to a plurality of different heights corresponding to children's women's and men's lasts; means for effecting a fine adjustment of the support heightwise to make said adjustments correspond to lasts of dif-

ferent last makers, and means for maintaining the means for effecting fine adjustment against accidental displacement.

23. In a machine of the class described, the combination of a heel band for conforming an upper to the rear end of a shoe, wipers for treating the overlasted portion of the upper and counter, a shoe support movable toward and from the machine to present a shoe to the band and wipers, means for adjusting the shoe support to a plurality of different heights, a screw arranged to effect a fine adjustment of all of said other adjustments together, and a set-screw for holding said fine adjustment screw in adjusted position.

24. In a machine for operating on turn shoes, the combination of a shoe support, a pair of wipers, a movable carrier on which the rear ends of the wipers are pivoted, a pair of slides arranged for movement in directions transverse to the direction of movement of the carrier, each slide comprising two members having limited relative movement lengthwise of the slide, springs normally holding the slide members extended to the limit, mechanism between the carrier and each of the slides for movement equally and oppositely toward and from each other, and pivotal connections between the forward ends of the wipers and the adjacent ends of the slides.

In testimony whereof I have signed my name to this specification.

JOSEPH FAUSSE.
